UNITED STATES PATENT OFFICE.

ALFRED LARSSON, OF STOCKHOLM, SWEDEN.

DESIGN FOR A TELEPHONE-CABINET.

No. 39,464.

Specification for Design.

Patented Aug. 25, 1908.

Application filed May 22, 1908. Serial No. 434,423. Term of patent 14 years.

To all whom it may concern:

Be it known that I, ALFRED LARSSON, a subject of the King of Sweden, residing at Stockholm, in the Kingdom of Sweden, have invented a new, original, and ornamental Design for Telephone-Cabinets, of which the following is a specification, reference being had to the accompanying drawing, forming a part thereof.

The figure is a perspective view of a telephone cabinet, showing my design.

I claim:

The ornamental design for a telephone cabinet, as shown.

ALFRED LARSSON.
